US0D1084707S

(12) **United States Design Patent** (10) **Patent No.:** **US D1,084,707 S**
(45) **Date of Patent:** **** Jul. 22, 2025**

(54) **DUSTPROOF COVER**

(71) Applicant: **Tao Song**, Jiangxi (CN)

(72) Inventor: **Tao Song**, Jiangxi (CN)

(**) Term: **15 Years**

(21) Appl. No.: **29/987,126**

(22) Filed: **Jan. 21, 2025**

(51) **LOC (15) Cl.** **06-13**

(52) **U.S. Cl.**

USPC **D6/610**

(58) **Field of Classification Search**

USPC D3/301; D6/595, 608, 610, 611, 617,
D6/685; D21/811, 834; D30/108, 119

CPC E04H 15/40; E04H 15/44; E04H 15/405

Primary Examiner — George J Ulsh

Assistant Examiner — Bethany Louise Mallino

(57) **CLAIM**

The ornamental design for a dustproof cover as shown and described.

DESCRIPTION

FIG. 1 is a perspective view of a dustproof cover showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The dash-dash broken lines in the drawings depicting portions of the dustproof cover form no part of the claimed design. The dash-dash broken lines depicting environment form no part of the claimed design.

1 Claim, 8 Drawing Sheets
